UNITED STATES PATENT OFFICE.

JOSEPH SEVERSON, OF OZONE PARK, LONG ISLAND, NEW YORK.

NUMBERING FIXTURE.

Application filed June 17, 1920. Serial No. 389,680.

To all whom it may concern:

Be it known that I, JOSEPH SEVERSON, a citizen of the United States, and resident of Ozone Park, Long Island, county of Queens, 5 and State of New York, have invented a new and Improved Numbering Fixture, of which the following is a full, clear, and exact description.

In connection with engraving machines 10 utilized in applying engraving numbers in various devices, it is a well appreciated fact that the conventional machine usually includes a work block upon which an engraving stylus is moved by means of a pantograph, a tracing stylus being associated with 15 the pantograph which tracing stylus moves over the table adapted to receive the master blocks, which as is well known, include slugs of metal bearing upon them a carefully engraved design representing a numeral, letter, etc.

Heretofore, when it has been desired to change the reading of these blocks, so that a different engraving might be applied, it 25 has been customary to release a set screw provided for this purpose, so that the blocks might be removed one by one, and substituted for the slugs desired.

This has been at best but a cumbersome 30 expedient, in view of the fact that it has been necessary for the operator to have a great number of substitute slugs lying upon the work table before him, which slugs were liable to become misplaced, broken, etc.

Having these defects in mind, it is now 35 an object of my invention to provide a numbering fixture which is more particularly adapted as a substitute for the master blocks heretofore utilized for this purpose, al- 40 though this fixture might be applied to any desirable use.

A further object of my invention is the construction of a numbering fixture, by 45 means of which any suitable reference characters may be immediately presented, so that they may be utilized in operating the tracing stylus, and which will further be held against movement when the same are in correct position.

Reference is had to the attached sheets of 50 drawings as illustrating one practical embodiment of my invention, and in which,

Figure 1 is a diagrammatic view of an 55 engraving machine of the type specified, with my improved numbering fixture applied thereto.

Figure 2 is a sectional end view taken along the lines 2-2 of Figure 3.

Figure 3 is a sectional side view taken along the lines 3-3 of Figure 2.

Figure 4 is a front view of a certain detail of numbering fixture.

Figure 5 is a side view of the same, partly in section, and taken along the lines 5-5 of Figure 2, and

Figure 6 illustrates a detail of numbering fixture.

In these views the reference numeral 10 indicates a standard of an engraving machine which may be of the type illustrated 70 in United States Patent 542,902 and which has a work block 11 associated therewith. Arranged above the work block 11 and adapted to travel over its surface is a conventional engraving stylus 12, which is 75 moved by means of any desirable type of pantograph 13, operated by the tracing stylus 14 overlying the operating table 15, having applied thereto my improved type of fixture.

It is now customary, as aforesaid, to mount the master blocks upon the operating table, and to clamp them thereon by means of a set screw. Upon different pieces to be serially numbered being positioned 85 upon the work block 11, it has been necessary to loosen the set screw, and to each time substitute a different master block to produce the result desired. These blocks have subsequently dropped, become lost or 90 broken, aside from the fact that a great amount of time was always required to properly remove and re-apply the desired block.

My numbering fixture, which aims to 95 overcome these defects, now conveniently includes a U shaped bracket 16, which is preferably provided with a stud 17, which serves, by virtue of a co-operating screw 18 attached to the operating table 15, to retain 100 the numbering fixture in applied position.

The rod 19 preferably has its ends extending through the upper ends of the bracket 16, and serves as a medium whereby numbering fixtures may be rotatably 105 mounted. Each of these blocks conveniently includes a multi-faced disk 20, having a reference character applied to each of its faces.

It will be understood, that by the construction provided, that the working table 110 will at all times have applied to it, a numbering fixture presenting any desirable types.

of reference characters, which may be varied at will, by rotating the disk 20 to bring that reference character to be traced uppermost, so that the tracing stylus 14 may be 5 passed over the same with a view of properly operating the engraving stylus 12, thus eliminating all difficulty incident to the altering of the reading appearing upon the operating table 15.

- 10 To now provide means which will serve to normally hold each of the disks against rotation, but will permit of a ready freeing of any of the same so that they may be freely rotated, the arms of the brackets 16 are preferably formed with a cutout portion arranged at an angle, and having its faces, corresponding to the angle of the face lying adjacent the same when the uppermost face of the disk is in a horizontal position.
- 15 20 Into this cutout portion is inserted a bar 21 which may be secured in this position by any desirable means.

The bar 21 is formed with a series of recesses 22 in one of its faces corresponding 25 in number to the number of disks forming a part of the numbering fixture, a further recessed portion 23 is conveniently in communication with the recesses 22, and a passage 24 extends from the former through 30 to the opposite face of the bar.

A shoe 25 is now positioned within the recesses 22, a shank 26 being provided, which shank extends through the passage 24 and the recess 23, it being noted that a spring 27 of any desired type is conveniently interposed between the under side of the shoe 25, and has its opposite end extending within the recess 23, thereby serving to project through and prevent a movement on the part 40 of the corresponding disk 20.

To now provide means which will permit of the quick disengagement of the shoe 25 from the face against which it bears, an operating lever 28 is conveniently associated 45 with the outer face of the bar 21, and is formed adjacent its inner end with a cam surface 29 projecting beyond the point 30 of pivot.

It will now be understood, referring to 50 the position of the parts, as has been shown in Figures 2 and 5, that the shoe 25 will bear against the face of the disk 20, so that any movement of one with respect to the other will be precluded. Upon the operating lever 28 being rocked however, the cam end 29 of the same will serve to retract the shank 26, and thus move the shoe 25 out of engagement with the face of the disk 20 so

that a free rotation of this latter member may be effected.

Obviously numerous modifications of structure might readily be resorted to without in the least departing from the spirit of my invention.

Having thus described my invention, what 65 I claim as new and desire to secure by Letters Patent is as follows:

1. A numbering fixture including in combination with the tracing stylus of a pantograph, of a plurality of discs positioned adjacent said tracing stylus, said discs being movable with respect to one another.

2. A numbering fixture including in combination with the tracing stylus of a pantograph, of a plurality of discs positioned adjacent said stylus and movable with respect to each other, and means for normally preventing the movement of one with respect to the other of said discs.

3. A numbering fixture including in combination with the tracing stylus of a pantograph, of a bracket positioned adjacent said stylus, a rod extending between the arms of said bracket, a plurality of discs rotatably mounted upon said rod and means for normally preventing a rotation of said discs.

4. A numbering fixture adapted to be positioned adjacent the pressing stylus of a pantograph, said fixture including a bracket, a rod mounted upon said bracket, a series 90 of multi-faced disks rotatably mounted upon said rod, said bracket being formed with cutout portions, and locking means for said disks mounted within said cutout portions.

5. A numbering fixture adapted to be positioned adjacent the pressing stylus of a pantograph, said fixture including a bracket, a rod mounted upon said bracket, a series of multi-faced disks rotatably mounted upon said rod, said bracket being formed with 100 cutout portions extending at an angle, and locking means for said disks mounted within said cutout portions.

6. A numbering fixture, including a U shaped bracket, a rod extending between the 105 arms of said bracket, multi-faced disks rotatably mounted upon said rod, the arms of said bracket being cutout adjacent their edges, a bar, formed with a number of recesses corresponding to the number of disks 110 mounted upon said rod, mounted within said cutout portions, shoes within said recesses, means for projecting said shoes against one of the faces of said disks, and means for retracting said shoes.

JOSEPH SEVERSON.
